Joseph L. Levy

UNITED STATES PATENT OFFICE.

JOSEPH GOLDSMITH, JR., OF CHICAGO, ILLINOIS.

HAIR-CURLING DEVICE.

1,406,639.

Specification of Letters Patent. Patented Feb. 14, 1922.

Application filed January 22, 1921. Serial No. 439,069.

To all whom it may concern:

Be it known that I, JOSEPH GOLDSMITH, Jr., a citizen of the United States, and a resident of the city of Chicago, county of Cook, and State of Illinois, have invented a certain new and useful Improvement in Hair-Curling Devices, of which the following is a specification.

This invention relates to a hair curling or crimping device and has for its object to provide a device of this character which receives and retains the hair and aid in producing a curled or waved appearance of the hair.

This object is attained by means of my device, which consists generally of a strip of flat resilient material bent upon itself to form a pair of opposing arms which receive, grip, press and crimp the hair between them, a strand of hair usually being spirally wound on one of these arms and an improved arrangement being provided by means of which the ends of the arms may be detachably locked together.

A further object of my invention is to provide a device of this character in which the two arms can be readily locked together so that they cannot inadvertently separate while the device is in use and a still further object of my invention is to provide a locking device for the two arms which has no protruding points or ends to injure the hair or the head.

With these objects and other objects which may hereinafter appear in view, I have devised the particular arrangement of parts hereinafter set forth and more particularly pointed out in the claims appended hereto.

Reference is to be had to the accompanying drawing forming a part hereof in which—

Figure 1 is a plan view of my improved hair curling device in its closed position.

Figure 2 is a bottom view of the ends of the spring arms showing the device for detachably locking the same together.

Figure 3 is a sectional view on the line 2—2 of Figure 2 looking in the direction of the arrows.

Figure 4 is a sectional view on the line 4—4 of Figure 1 looking in the direction of the arrows,

Figure 5 is a side elevation of the device in its open position,

Figure 6 is a transverse sectional view 55 of the sliding guard, and

Figure 7 is a plan view of a modified form of guard.

Throughout the various views of the drawings similar reference characters designate 60 similar parts.

In the preferred embodiment of my invention, as illustrated in the accompanying drawing, the hair curling device is preferably constructed of a continuous strip of 65 flat, resilient material transversely folded upon itself to form a loop 1 and a pair of oppositely disposed normally separated spring arms 2 and 3. The arm 2 is provided at its end with a tapered portion bringing 70 the end down to a point 4.

The other arm 3 is provided with a locking device in the nature of a slidable sleeve member 6 which forms a combined locking device and guard member for the ends of two arms 75 2 and 3. This guard member is provided on its upper face with a raised crown portion 7 which is centrally situated and of substantially the same contour or shape as the tapered end 4 of the arm 2. It will be seen 80 that when the guard member is held over the end of the arm 2, the tapered portion 4 of said arm fits into the crown portion 7 on the guard whereby lateral movement of the arm 2 is avoided. The under face of the 85 guard member 6 is cut away or recessed as at 8 and 13. The guard member 6 is slideable on the end of the arm 3 and the sliding movement of the same thereon is restricted by means of a pair of spaced-apart stops 9 90 and 10. The stops 9 and 10 are in the nature of elongated protuberances formed by distorting or forcing outward the material of the spring arm 3. As the under face of the guard member 6 is cut away as at 8 and 95 13, the guard member is thus provided with a narrow portion 11 which lies between the two stops 9 and 10 and permits the sliding movement of the guard member 6 on its arm 3. Situated between the stops 9 and 10 on the arm 3 is provided a friction-causing means in the nature of a pressed-out hump or projection as at 14. As the narrowed tongues 11 on the guard are resilient,

these tongues ride over the projection 14 with friction thus frictionally resisting movement of the guard and preventing inadvertent opening of the device.

- 5 The guard member 6 is provided with a lug 15 which projects downwardly into the entrance to the guard. The arm 2 is provided near its end with an aperture or perforation 16 to receive said lug 15 and cause a 10 locking engagement between the guard member 6 and the arm 2. In Figure 7 a modified form of guard member is shown in which the locking lug is formed by slitting the guard member as at 16 and 17 and bending 15 the material 18 between the slits downwardly. From the foregoing it will be apparent that the locking lug may be formed in many other ways without departing from the spirit of my invention.
- 20 In using my improved hair curling device a strand of hair is wound spirally about the arm 2 and the arms 2 and 3 are pressed together while the slidable guard member 6 is in the position shown in dotted 25 lines in Figures 1 and 2. When the two arms are brought together the guard member 6 is moved to a position so that it abuts against the stop 9 and slides over the end of the arm 2. The tendency of the arms 30 2 and 3 to spring apart causes the projecting locking lug 15 on the guard to snap into engagement with the opening 16 in the arm 2, as disclosed in Figure 3, thus holding the two arms together securely. To release the 35 arm 2 the two arms 2 and 3 are pressed together adjacent their ends so that the sleeve may be slid over the end of the arm 2 and the arms then spring apart to the position disclosed in Figure 5.
- 40 While I have shown the projection 15 on the guard 6 in the nature of a downwardly or laterally bent lug, it will be understood that any type of projection may be formed on said guard either by distorting or forcing outward the metal therein or in any other way. The opening 16 in the arm 2 may also be varied in shape or size to suit the projection formed on the guard 6.
- 45 50 From the foregoing it is obvious that my invention is not to be restricted to the exact embodiment shown but is broad enough to cover all structures coming within the scope of the annexed claims.
- 55 What I claim is:

1. A device of the class described comprising a hair curler having a pair of resilient arms, a slidable guard on one of said arms adapted to be moved to overlie the 60 end of the other arm, the guard having a projection and one of said arms having an opening adapted to receive said projection.
2. A device of the class described comprising a hair curler having a pair of arms, 65 a slidable guard carried on one of said

arms, a tapered end on the other arm, a raised crown portion on the guard adapted to overlie the tapered end on the last mentioned arm, a projection on said crown portion, said last mentioned arm having an 70 opening to receive said projection.

3. A device of the class described comprising a hair curler having a pair of arms, a guard member movable on one of said arms, the other arm having an opening and a 75 projection on the guard for engaging with said opening to cause a locking engagement between said arm and the guard.

4. A device of the class described comprising a hair curler having a pair of resilient arms, a slidable guard member on one 80 of said arms and movable over the end of the other arm, said last mentioned arm having an opening and a downwardly bent lug on the guard member adapted to be 85 received in said opening.

5. A device of the class described comprising a hair curler having a pair of arms, a guard member slidably mounted on one 90 of said arms and adapted to be moved to engage with the other arm and hold both of the arms together, said guard member having a downwardly extending lug, and one of said arms having an opening to receive said lug. 95

6. A device of the class described comprising a hair curler having a pair of arms, a slidable guard on one of said arms adapted to be moved to overlie the end of the other arm and a projection on the arm on 100 which the guard is mounted and over which said guard is adapted to slide, said projection being adapted to frictionally contact with a portion of the guard and frictionally resist slidable movement of said guard. 105

7. A device of the class described comprising a hair curler having a pair of arms, a slidable guard member mounted on one 110 of said arms and adapted to be moved to overlie the end of the other arm and hold the ends of both of the arms together, a projection on one of said arms and a resilient portion on the guard member adapted to frictionally contact with said projection for frictionally resisting movement of the 115 guard.

8. A device of the class described comprising a hair curler having a pair of arms, a slidable guard member on one of said arms adapted to be moved over the other 120 arm, said last mentioned arm having an opening, a lug on the guard member adapted to engage said opening, and means for frictionally resisting slidable movement of the guard member on the arm on which it 125 is mounted.

9. A device of the class described, comprising a hair curler having a pair of resilient arms, a slidable guard member on one of said arms, a pair of spaced apart 130

stops on said arm adapted to limit movement of the guard member and a projection intermediate of said stops contacting with and frictionally resisting sliding movement of the guard member.

10. A device of the class described comprising a hair curler having a pair of arms, a sliding guard movable on one of said arms and adapted to be moved to overlie 10 the other arm, a pair of spaced apart stops on the arm on which the guard is mounted,

said guard having a narrowed portion movable between said stops and means situated between said stops for contacting with the narrowed portion of the guard and adapted 15 to frictionally resist movement of said guard.

Signed at the city of Chicago, county of Cook, and State of Illinois, this 20th day of January, 1921.

JOSEPH GOLDSMITH, JR.
